— FIG. 1 —

INVENTOR

AGNES M. HILLS.

By C. F. Blake

ATTY

UNITED STATES PATENT OFFICE.

AGNES M. HILLS, OF STANFIELD, OREGON.

WASHING-MACHINE.

1,333,916.

Specification of Letters Patent. Patented Mar. 16, 1920.

Application filed August 6, 1917. Serial No. 184,775.

To all whom it may concern:

Be it known that I, AGNES M. HILLS, a citizen of the United States, residing at Stanfield, county of Umatilla, State of Oregon, have invented certain new and useful Improvements in Washing-Machines, of which the following is a specification.

My invention is illustrated in the accompanying drawing, which therefore forms a part of this application for Letters Patent, and in which:

The figure is a perspective view of my invention, parts being broken away to best illustrate the construction.

15 In materializing my invention I have employed a reservoir 2, having therein and substantially concentric therewith a compartment 3, there being a space intermediate said compartment and said reservoir upon 20 all sides and the bottom thereof.

The compartment is open at the top, and is there connected with flanges 4 to the reservoir, said flanges closing the top of the spaces intervening between the sides of the 25 compartment and the sides of the reservoir.

The bottom of said compartment is perforated with a plurality of orifices 5, as are likewise the sides thereof for a certain distance downward from the top, perforated 30 with orifices 6.

A cover 7 closes the top of the compartment 3, said cover being hinged to the reservoir 2 by hinges 8 and rod 9, and having a suitable locking mechanism, which latter 35 is illustrated as a hasp 10 and staple 11.

Disposed within compartment 3 is a dasher composed of a plurality of alternately vertically inclined members 12 the adjacent of said members being integrally 40 joined at the coincident edges thereof, thus forming a series of respectively inverted re-entrant angles.

Suitable operating levers 14 are pivotally mounted upon rod 9, and at the opposite end 45 thereof are connected by a handle 15, said levers being substantially parallel longitudinally to the inclined members 12.

Said members 12 are perforated as shown at 13.

50 Upwardly projecting from dasher 12, and integral therewith, are hollow rods 16, which rods project above cover 7 through longitudinal slots therein.

Depending from each of levers 14, and integral therewith, are rods 18, which rods respectively enter the hollow rods 16, and are

adjustably secured therein by means of pins 19 inserted in holes in said hollow rods 16 and their respective coacting rods 18.

Because of thus being rigidly secured to 60 levers 14 the dasher is given an angular reciprocating motion identical therewith about the pivotal mounting point thereof, which motion causes the water to be forced in a plurality of streams out of the inverted 65 angular troughs of said dasher over the material to be washed.

In operation the articles to be washed are placed in compartment 3, together with a suitable amount of water and soap, or 70 other cleansing material, the cover 7 is closed and locked, and the dasher 12 is adjusted to suit the amount of material to be washed within compartment 3 by means of pins 19. 75

The dasher 12 is then vertically reciprocated by operating levers 14, which reciprocation alternately compresses and releases the material being washed.

When the material is compressed some of 80 the water or cleansing fluid is forced upward through orifices 13 in dasher 12 and some is forced downward through orifices 5 in the bottom of compartment 3.

The latter traverses the space intermediate 85 compartment 3 and reservoir 2, and if sufficient, emerges therefrom through orifices 6 in compartment 3, and descends within said compartment in the form of small streams or spray. 90

The volume of the space intermediate compartment 3 and reservoir 2 is so great relatively to that of the combined orifices 5 in the bottom of said compartment that a very slow velocity flow or circulation of 95 water is obtained within said space, thus allowing the dirt removed from the material within compartment 3 to settle within said intermediate space, whence it may be withdrawn in any convenient manner, as by a 100 faucet or hose inserted in orifice 20 provided therefor.

My invention may be made of any size or shape and constructed of any material deemed convenient and suitable for a device 105 of this character, and while I have illustrated and described a form of construction and arrangement of parts found desirable in materializing my invention, I wish to include in this application all mechanical 110 equivalents or substitutes that may fairly be considered to come within the scope and

purview of my invention as defined in the appended claims.

Having disclosed my invention so that others skilled in the art may be enabled to construct and to use the same, what I wish to claim as new and to secure by Letters Patent is:—

1. In a washing machine, a reservoir; a compartment within said reservoir, attached thereto at the top, forming an inclosed space therebetween; a cover hinged to one side of said compartment substantially at the point of juncture thereof with said reservoir; levers mounted upon the pin of said cover hinge; tines integral with said levers and downwardly projecting therefrom into said compartment; and a dasher adjustably mounted upon said tines and composed of a series of pairs of relatively inclined intersecting planes, the lines of intersection

thereof being in vertical planes parallel to vertical planes passing through the axes of said levers, said dasher having an oscillating motion about said hinge pin.

2. In a washing machine a reservoir; a dasher within said reservoir; a lever pivotally mounted upon said reservoir above the same; and means to cause said dasher to receive from said lever an angular reciprocating motion about said pivotal mounting point.

In witness whereof I claim the foregoing as my own, I hereunto affix my signature in the presence of two subscribing witnesses, at Stanfield, county of Umatilla, State of Oregon, this 24th day of July, 1917.

AGNES M. HILLS.

Witnesses:

RALPH A. HOLTE,
CLEM HOWARD.
